FIREARM

Eugene G. Reising, Hartford, Conn.

Application February 7, 1941, Serial No. 377,867

6 Claims (Cl. 42—3)

This invention relates to firearms and presents improvements over the invention disclosed in my co-pending application Serial No. 342,979, filed June 28, 1940, for Firearms.

Objects of the invention include the provision of a firearm having selector means whereby it may be fired in semi-automatic or fully automatic conditions, and in which the selector is effective to act as a safety device; the provision of means to prevent any possible accidental fire when the bolt is not in locked condition; and the provision of a firearm as recited which is simple and efficient in operation and construction.

Other objects and advantages of the invention will appear hereinafter.

Reference is to be had to the accompanying drawing, in which

Fig. 1 is a view in central longitudinal section thru the receiver showing the parts in cocked condition for semi-automatic fire;

Fig. 2 is a view in elevation with parts broken away and showing the selector in position for semi-automatic fire;

Fig. 3 is a detail view which shows the selector in safety position; and

Fig. 4 is a detail view which shows the automatic connector and selector in position for fully automatic fire.

Referring in detail to the drawing, the numeral 10 indicates the stock of the firearm, and 11 indicates the forepiece, these parts being broken away for illustrative purposes. A receiver 12 is secured to the fore-piece as by a stud or other means 13 which may be screwed into or otherwise fastened to the parts. A barrel 15 is fastened to the receiver in any desired manner.

A breech-bolt 16 is slidably mounted in a longitudinal chamber 17 in the receiver, and the bolt is provided with a longitudinal central firing-pin 18 which is normally urged rearwardly by a firing-pin spring 19. This firing pin extends in position to fire a shell in the breech as illustrated in my aforesaid application, and is limited in its travel by pin 20 entering a recess in the side of the firing pin. An extractor and ejector of conventional design may be used, these elements not being here shown for clarity of illustration.

Chamber 17 has a retarding recess 21 in its upper side of the same cross-section as the breech-bolt, and this recess terminates in a beveled retarding shoulder 22 to receive a corresponding bevel on the rear end of the bolt as shown in Fig. 1. A recess 23 is formed on the underside of the bolt, this recess having its forward end wall 24 beveled toward the rear to contact a

similar beveled shoulder 25 on the forward end of a lug 26 fixed at the rear end of an action bar 27. The action bar is longitudinally slidable in the manner disclosed in my aforementioned application, being normally urged forwardly by a spring 28 which bears at one end against the action bar as on forward lug 29 and at the other end against stud 13. A rod 30 locates the spring, and the action bar has a finger piece 31 for manual operation thereof accessible thru a bottom slot in the fore-piece 11.

A magazine 33 extends upwardly thru an opening in the fore-piece and in position to deliver cartridges into the breech, and an ejector opening 34 is provided in the receiver. The cartridges will seat in the path of movement of the bolt 16 as illustrated in my said application.

A screw plug 35 threaded into the rear end of the receiver closes chamber 17, and this plug has a spring-supporting rod 36 for a hammer spring 37. Hammer 38 is generally hollow and cylindrical and fits over the rod and spring and is thus constantly urged forwardly for contact with the firing pin 18. The forward end of the hammer has an aperture 39 slightly larger in diameter than the firing pin, and a pair of longitudinally spaced shoulders 40, 41, which are adapted to be successively engaged by a complementary shoulder on a sear 42, on the rearward stroke of the hammer. The sear is pivoted on a sear pin 43 mounted on a sear supporting lug 44 depending from the receiver, and is spring-pressed into engagement with the hammer shoulders as shown in Fig. 1. The sear has a firing shoulder 45 located intermediate its height and a lateral depending leg 46 for a purpose to be described.

Firing shoulder 45 is adapted for engagement with a complementary shoulder 47 on a disconnector 48 which is pivotally mounted at its rear end at 49 on a pivoted trigger 50 and extends forwardly ending in a cam surface 51 located in the path of movement of the action bar lug 26. The trigger 50 is spring-pressed in a forward direction by trigger spring 52 and the disconnector is urged upwardly by disconnector spring 53.

An action bar supporting stud 54 is provided with a notch 55 to receive a lip 56 on lug 26 to support the action bar at the forward end of its stroke, and the lug has a beveled surface 57 adapted for engagement with a complementary surface 58 in recess 23 in the bolt 16 for manual operation of the bolt by finger piece 31.

An automatic connector 59 for fully automatic fire is pivotally mounted on a connector pin 60 on the depending leg 46 of the sear 42. The con-

necter is spring-pressed downwardly at its rear end by connector spring 61 which may be mounted conveniently in the sear lug 44 or other element. At its forward end, the connector terminates in an upwardly extending hook 62 adapted for selective engagement with a notch 63 in the action bar lug 26. The trigger 50 is provided with a lift pin 64 for engagement with a rear surface 65 on the connector to hold the latter out of the path of action bar lug 26.

The disconnector 48 is provided with a forwardly extending lug 66 and the automatic connector has a short flange 67 with a guide lip 68. The receiver slidingly mounts a selector element 69 having a thumb piece 70 and a pointer 71 for alignment with three stations marked S for safety, SA for semi-automatic, and FA for fully automatic, as shown in Figs. 2 and 3. A strap 72 depends from the selector and has an end flange 73 which controls the parts to lock the connector and disconnector against any firing action, as seen in Fig. 3, i. e., neither of these elements can rise and the disconnector is cammed out of engagement with the sear.

With the selector on position SA, as seen in Figs. 1 and 2, the disconnector 48 is freed of the flange 73 and the firearm is operable semi-automatically as the trigger will cause the disconnector to actuate the sear each time it is pressed. However, in this position of the selector the automatic connector 59 is still prevented from rising by the selector flange and therefore it is not operable, as the sear movement will only reciprocate the connector slightly and this does not affect the fire, while the lift pin 64 only has the effect of depressing hook 62.

If the selector is placed at position FA, the selector flange 73 will be free of both the connector and disconnector, see Fig. 4, and therefore as the trigger is pulled and the lift pin disengages surface 65 of the connector, the latter's spring 61 will pivot the connector counterclockwise on pin 60, and hook 62 will be in position to engage in recess 63 in the action bar lug 26. Hence the action bar causes firing action of the sear when it reaches its forwardmost position under influence of spring 28 by pulling forwardly on the connector, and the firearm will be seen to automatically fire until the trigger is released and the lift pin 64 engages the connector to move hook 62 out of the path of the action bar lug 26. It is to be noted that this construction does not impair or in any way affect the delayed action of the bolt 16, which always is located in raised position as shown in Fig. 1, at the instant the action bar lug reaches its forwardmost position to release the sear.

It is a possibility that the hammer might not move to the left far enough to be stopped by the sear and therefore could follow the bolt and actuate the firing pin prior to locked condition of the bolt. Therefore, the notch 40 is provided, so that the hammer will be cocked even though not in normal cocking position. Also, the aperture 39 will insure that, even if the hammer did follow the bolt to the right, the firing pin could not be actuated until it is raised to its off-center position in locked condition of the bolt. These features provide a double safety against accidental pre-firing.

Having thus described my invention and the advantages thereof, I do not wish to be limited to the details herein disclosed, otherwise than as set forth in the claims, but what I claim is:

1. A firearm having a support, a receiver mount-

ed on said support, a breech bolt chamber in said receiver, firing mechanism including a hammer, a sear for latching the hammer, a reciprocable breech bolt in said chamber, and a firing pin in said breech bolt for engagement by the hammer upon release of the latter by the sear, an action bar engaging said breech bolt, spring means urging said action bar forwardly, a connector pivoted on said sear, a connector spring urging said connector toward said action bar, interengaging means on said action bar and said connector, said interengaging means being adapted to connect said bar and connector on the forward stroke of the former and to disconnect them on the rearward stroke, a barrel on said receiver, a spring-pressed trigger normally engaging said connector and holding it disengaged from said action bar against the action of the connector spring.

2. A firearm having a support, a receiver on said support, a breech bolt chamber in said receiver, a breech bolt located in said chamber for reciprocation therein, an action bar reciprocably mounted adjacent said receiver and having means to urge it forwardly, said action bar being engaged with said bolt, a recess in said action bar, a sear pivotally mounted on said receiver, a connector pivoted to said sear, a lug on said connector adapted for positive locking engagement in said recess, a connector spring urging said connector to lug-engaging position, means selectively effective to interdict the spring action, a barrel on said receiver, and a trigger normally bearing on the connector and moving the latter out of lug-engaging position against the action of the connector spring.

3. In a firearm, the combination of a support, a receiver having a barrel on said support, a breech bolt chamber in said receiver, firing mechanism on said support including a breech bolt located for reciprocatory motion in said chamber, an action bar slidably mounted on said support and engaged with said bolt, and means normally urging said action bar forwardly; with a sear, a disconnector adapted to engage said sear, a trigger, said disconnector being secured to said trigger, a connector mounted on said sear, and interengaging means on said action bar and said connector effective to draw said connector forwardly at the forwardmost limit of movement of said action bar.

4. The combination recited in claim 3 including selector means selectively movable to a position wherein it engages and holds said connector and disconnector, and to a position wherein it engages and holds said connector alone.

5. The combination recited in claim 3, including means on said trigger adapted to move said connector in a direction opposite to its spring-urged movement.

6. In a firearm the combination of a receiver, a breech bolt in said receiver, a hammer in said receiver, a sear cocking said hammer in spaced relation to said bolt when the latter is in breech-closed position, and a firing pin in said bolt for engagement by the hammer upon release of the latter by the sear; with means for providing automatic fire of said firearm including a trigger, a spring normally urging said trigger in one direction, a bar mounted to reciprocate parallel to said bolt, said bar and bolt being interengaged, a spring normally urging said bar and therefore said bolt to breech-closed position, an element connected to said sear, said element forming a connector having means for engagement with said bar whereby the latter will pull the former and

therefore said sear to hammer-releasing condition at the end of the stroke of the bolt to breech-closed position, means for disengaging said bar from said element upon retraction of the bolt and hammer due to the explosion of a shell, a 5 spring to reset the sear when said bar and connector element are disengaged, means on said trigger normally maintaining said connector ele-

ment out of position for engagement with said bar while said trigger is in its spring-urged position, and a spring for positioning said connector element in position to be engaged by said bar upon movement of said trigger in the opposite direction.

EUGENE G. REISING.
